[57] CLAIM

The ornamental design for a face saver mask for facial massaging, as shown and described.

DESCRIPTION

FIG. 1 is a front elevational perspective view of the face saver mask for facial massaging embodying our new design;

FIG. 2 is a top plan view thereof, with the straps being partially broken off for ease of illustration;

FIG. 3 is a front elevational view thereof;

FIG. 4 is a right side view thereof; the left side view being a mirror image thereof;

FIG. 5 is a bottom plan view thereof; and,

FIG. 6 is a rear elevational view thereof.

FIG. 6
